HYDRAULIC PUMPING SYSTEM FOR PRODUCING FROM OVERLYING RESERVOIRS

Louis F. Davis, Harry N. Stansbury, Jr., and Marshall O. Crumbaker, Dallas, Tex., assignors to The Atlantic Refining Company, Philadelphia, Pa., a corporation of Pennsylvania

Application November 6, 1948, Serial No. 58,652

7 Claims. (Cl. 103—46)

1

This invention relates to an improved system for producing from a plurality of subterranean oil reservoirs. More particularly, the invention relates to a system including hydraulic pump means for producing from a plurality of oil reservoirs through a single well without commingling of the fluids from the several reservoirs.

The search for oil has led to the discovery in certain oil fields of a number of producing zones. Generally, the characteristics of these producing zones are dissimilar and frequently both oil and gas reservoirs are encountered. In the case of oil reservoirs, to which the present invention is primarily directed, the pressure exerted on the oil contained therein may be attributable to a water drive, for example, or the presence of dissolved gaseous hydrocarbons. Further, there may be a considerable variance in the quantum of pressure exerted on the various reservoirs in the field.

Joint production of oil from two or more producing zones through a single casing or tubing string is likely to result in irreparable damage of the reservoirs and wastage of the fluids contained therein due to drainage of fluid from one reservoir into a reservoir of lesser pressure and the attendant pressure drive reduction in the former. For the above reasons and the fact that in substantially all States in which oil is being produced from subterranean petroliferous zones laws have been enacted imposing restrictions on the production of oil and gas, or either, as the case may be, from two or more producing zones in an oil field, efforts have been directed to the development of a method and apparatus for independently producing oil from a plurality of overlying reservoirs.

Obviously, this could be accomplished by producing separately each of the reservoirs through a well or wells communicating solely therewith; however, relatively high drilling costs make desirable the production from the producing zones through a single bore hole. In this regard, little difficulty is experienced in the case of reservoirs having sufficient pressure exerted thereon by a water drive, for example, to produce the same without employment of artificial lift means. For this purpose a tubing string having a packer provided on the end thereof is run into a bore hole which traverses the reservoirs and is lined with a well casing having perforations therein communicating with each of the reservoirs. The well packer is set intermediate an upper and lower producing zone, whereby fluid from the upper producing zone will flow into the well casing and

2

thence to the well surface through the annular space between the casing and tubing string, and fluid from the lower producing zone will be directed into the tubing and will flow therethrough to the well surface. As the reservoirs are produced, the reservoir pressures will be reduced and this will continue until the pressure drives are insufficient to cause fluids contained therein to flow to the well surface. Natural flow having ceased, the reservoirs may then be put on artificial lift to recover an additional amount of reservoir fluid. The same situation obtains in the case of reservoirs in which the initial pressure is insufficient to permit natural flow of reservoir fluid.

A modification of the system described above, which has been proposed for producing separately from two or more reservoirs having pressures such as to require artificial lift means, utilizes gas lift valves operable upon the establishment of a preselected differential in pressure thereacross. In this system, an inner tubing string is run inside the outer tubing string in a manner to provide an annular space therebetween and a packer is set externally of the inner tubing string and adjacent the lower end thereof, in a manner sealing the annular space between it and the outer tubing string, whereby reservoir fluid from the lower reservoir instead of flowing upwardly in the outer tubing string, as in the previous system, will be directed upwardly into the interior of the inner tubing string. Pairs of oppositely disposed gas lift valves are provided at spaced intervals respectively in the walls of the inner and outer tubing strings for lifting independently reservoir fluid from the lower reservoir and the upper reservoir, respectively. The gas lift valves may be actuated by injection of gas under pressure into the annular space between the inner and outer tubing strings. The valves are adjusted so as to be actuated by decreasing pressure differentials from the uppermost down to the lowermost pair of valves. The gas is injected at a pressure sufficient to actuate the uppermost pair of valves whereby the gas will pass therethrough and lift to the well surface the reservoir fluids above the uppermost pair of valves. In a similar manner, succeeding pairs of gas lift valves are actuated until the reservoir fluids above the lowermost pair of gas lift valves have been raised to the well surface. In practice, this system is unsatisfactory because the gas pressure at which the gas lift valves are actuated is dependent upon the pressures of the reservoir fluids in the annular

space between the outer tubing string and the casing, on the one hand, and within the inner tubing string, on the other hand, and, therefore, only partial control of this system from the well surface is possible. Further, in order to repair or replace the gas lift valves it is necessary to pull both the inner and outer tubing strings.

Other systems have been proposed for producing independently a plurality of producing zones through a single bore hole but none of these systems are entirely satisfactory for various reasons.

Accordingly, one object of the invention is to provide an improved system for producing from a plurality of subterranean reservoirs through a single bore hole, and a system that will obviate the difficulties above set forth.

Another object of the invention is to provide a system for producing from a plurality of producing zones through a single bore hole without commingling of the fluids from the several zones.

A further object of the invention is to provide a system for producing from a plurality of producing zones, the operation of which system may be controlled entirely from the surface of the well.

A further object of the invention is to provide a system including hydraulic pump means for separately lifting to the well surface reservoir fluid from a plurality of subterranean oil reservoirs through a single bore hole.

Other objects and features will be apparent from the drawings and description which follow.

Figures 1, 2, 3, and 4 are views, partially in section and partially in elevation, representing sequentially a well installation of apparatus constructed in accordance with the present invention.

Figure 5 is a cross-sectional view taken along the line 5—5 of Figure 6.

Figure 6 is a fragmentary, vertical cross-sectional view taken along the line 6—6 of Figure 5 showing in detail the manifold nipple of the secondary casing.

Figure 7 is a cross-sectional view taken along the line 7—7 of Figure 6.

Figure 8 is a cross-sectional view taken along the line 8—8 of Figure 9.

Figure 9 is a fragmentary, vertical cross-sectional view taken along the line 9—9 of Figure 8 showing the upper shoe.

Figure 10 is a cross-sectional view taken along the line 10—10 of Figure 11.

Figure 11 is a fragmentary, vertical cross-sectional view, partially in elevation, taken along the line 11—11 of Figure 10, showing the lower shoe.

Figure 12 is a vertical cross-sectional view, partially in elevation, showing the upper hydraulic pump with the pistons in their lowermost positions.

Figure 13 is a vertical cross-sectional view, partially in elevation, showing the lower hydraulic pump with the pistons in their uppermost positions.

In the drawings, 1 denotes generally the surface of the earth in which is run a bore hole including casing 2 traversing oil reservoirs 3 and 4, communicating with the interior of casing 2 through perforations 5 and 6, respectively. It is the purpose of the present invention to produce a plurality of reservoirs through a single bore hole and in particular at a time when the reservoir pressures are insufficient to cause the fluid to flow to the well surface except with the use of artificial lift means. It is also the pur-

pose of the present invention to utilize hydraulic lift means as the artificial lift means and in a manner such that the fluids from the several reservoirs will not be commingled.

To accomplish these results, there is disposed within casing 2 a first tubing string 7 in a manner providing a first annular space 8 between it and casing 2, and a second tubing string 9 within the first tubing string in a manner providing a second annular space 10 between it and the first tubing string 7. As will be seen in Figures 3 and 11, the second tubing string 9 is terminated short of the first tubing string 7 and at its end is provided with conventional ball check valve 11 for permitting the flow of fluid in one direction upwardly into the second tubing string 9. Also disposed within second tubing string 9 are hydraulic lift pumps 12 and 13, shown in detail in Figures 12 and 13, respectively, the two pumps being identical in construction with the exception of the end fittings securing them within the tubing string, the pump 12 as exemplified in Figure 12 being shown with its pistons in the lowermost position and pump 13 as exemplified in Figure 13 being shown with its pistons in the uppermost position. The construction and operation of these pumps will be hereinafter described.

In Figure 4, it will be noted that first tubing string 7 is terminated short of the end of casing 2 and preferably at a point above upper producing reservoir 3 to permit the inclusion of flow direction means for initially directing the flow of fluid from the several reservoirs 3 and 4, which flow direction means may consist of any one of several known mechanisms. The flow direction means exemplified in Figure 4 utilizes the conventional crossover packer mechanism. However, it will be apparent to persons skilled in the art that an anchor type packing mechanism may be employed with equally good results.

The crossover mechanism shown in Figure 4 comprises nipple 14 which is threaded as at 15 to the end of first tubing string 7, and as at 16 to sleeve 17 which terminates in ball check valve 18 for permitting the flow of fluid in one direction upwardly into sleeve 17. Also, threaded as at 19 to nipple 14 is expander 20 for cooperation with resilient packing element 21 secured as by bolts or rivets 22 to skirt 23. Screen 24 is threaded as at 25 to skirt 23 and is fixedly secured with respect to casing 2 by the expansion of production packer 26 placed intermediate producing reservoirs 3 and 4. Annular ring 27 is rigidly secured to sleeve 17 and cooperates with shoulder 28 of skirt 23 to support skirt 23 and packing element 21 free of expander 20 at the time of lowering first tubing string 7 and its dependent crossover mechanism into the well and until such time as production packer 26 is expanded, whence screen 24 and consequently skirt 23 will be frictionally held in fixed position for continued movement of expander 20 into packing element 21. Expander 20 will expand packing element 21 tightly against the inner wall of casing 2 and at the limit of its movement will be brought to rest, as at 29, against the end of skirt 23.

Further, in reviewing Figure 4, it will be seen that the fluid from reservoir 4, by reason of packer 26, will be directed through openings 30 of screen 24 and that also due to the press fit of shoulder 31 of skirt 23 against the outer wall of sleeve 17, will be directed through check valve 18 into sleeve 17 and thence through port 32 in nipple 14 into annular space 33 between the first

tubing string 7 and a secondary casing 34. Secondary casing 34 is pressed fit or otherwise rigidly secured as by threading, as at 35, to nipple 14 and continues upwardly within casing 2 to a point intermediate lower hydraulic pump 13 and upper hydraulic pump 12, at which point it is terminated in a closed end as by a pressed fit against manifold nipple 37, which nipple, as seen in Figure 6, also serves to secure successive sections of first tubing string 7, as at 38 and 39.

The fluid entering annular space 33 will continue to flow upwardly therein until reaching openings 40 in first tubing string 7 (Figures 2 and 6), where it will pass into the interior of first tubing string 7, and by reason of O-rings 36 and 41 and manifold nipple 37 will be further directed through openings 42 in second tubing string 9 into the interior thereof. The fluid entering into the interior of second tubing string 9 by reason of a block formed by header 43, as shown in Figure 9, again will be directed upwardly and into fluid chamber 44 on the intake side of hydraulic lift pump 12, the housing 45 of which is threaded on its intake side, as at 46, and on its power side, as at 47, to tubing string 9.

It will be noted that the openings 40 and 42 are positioned in tubing strings 7 and 9, respectively, intermediate the two hydraulic lift pumps 12 and 13. Attention is also called to the fact that O-rings, such as ring 36, are conventional and are in common use in the industry, and are typical of a number of such devices for sealing the annular space between two tubes.

The O-ring 36 is secured in place by commonly used assembly comprising, for example, nipple 48 provided with integral annular ring 49 against which is placed ring gasket 50 secured in position by O-ring retainer member 51 which also serves to support the O-ring 36 in position. O-ring 36 is secured in position on retainer member 51 by means of nut 52 and lock nut 53 threaded on nipple 48. The O-ring is required to be fitted only snugly within the tubing and is subsequently expanded into sealing engagement with the inner wall of the tubing by the pressure of liquid thereagainst. It is obvious, of course, that gasket 50 serves to prevent leakage of fluid through the threaded fittings for holding the O-ring in place.

The power liquid to pump 12 is supplied from a source, not shown, through valve controlled pipe 54 communicating with the interior of second tubing string 9 and, successively, with the power end of hydraulic pump 12 through openings 55 in screen 56 threaded, as at 51, into the pump housing 45. Pumps 12 and 13 are of the type generally known as "Kobe sub-surface production unit," and the construction and operation of which may be described as follows.

Referring to Figures 12 and 13, and in particular at this time to Figure 12 in which the pump is shown as having completed its down stroke, it will be seen that the power fluid entering through openings 55 of screen 56 will flow into chamber 58 and through passage 59 to apply pressure to head 60 of piston 61. It is to be understood that by down stroke is meant movement of the piston from the upper end of the cylinder, as shown in Figures 12 and 13, to the lower end thereof; and by up-stroke is meant movement of the piston in the opposite direction. During the down stroke of piston 61, the power fluid previously applied against head 62 of piston 61 for up-stroke movement is exhausted through passage 63 into annular opening 64 provided by valve 65 and

thence through port 66 into annular space 10. However, upon movement of piston 61 to the end of its down stroke, the power fluid in chamber 58 is caused to flow by reason of reduced head 67 of piston rod 68 through port 69 and into the space 70 beneath valve 65, whence valve 65 is caused to move upwardly whereby communication between passage 59 and chamber 58 and also between passage 63 and port 66 is broken, and simultaneously the annular opening 64 of valve 65 is moved adjacent passage 59 to establish communication between passage 59 and port 66, and port 71 in valve 65 is moved adjacent passage 63 to establish communication between chamber 58 and passage 63. When valve 65 is in its uppermost position it will be seen that the power fluid then will be caused to move from chamber 58 through port 71 and passage 63 and to be applied against head 62 of piston 61, whereby piston 61 will be caused to move to its uppermost position and the cycle repeated. It will be noted that valve 65 is limited in its downward movement by engagement of shoulder 72 against flange 73 formed integrally within housing 45.

During movement of piston 61 to its uppermost position, communication between chamber 58 and port 69 will be sealed by upward movement of piston rod 68. However, valve 65 will remain in its uppermost position until movement of piston 61 to the limit of its up-stroke whence annular cut out 74 in rod 68 will move into registry simultaneously with port 69 and bleed port 75 which together with the pressure of the power fluid against end 76 of valve 65 will cause the latter again to be moved to its lowermost position. It also will be noted that during the up-stroke of piston 61, the power fluid previously applied against head 60 thereof will be caused to flow through passage 59 and annular opening 64, and through port 66 into annular space 10.

Pump piston 77 is integrally connected with power piston 61 by middle rod 78 and will be caused to operate in synchronism therewith.

During the down stroke of piston 77, the reservoir fluid in chamber 44 will be drawn through passage 79 past ball check valve 80 and into cylinder 81. Also, during the down stroke of piston 77, the fluid from chamber 44 previously drawn into cylinder 81 at the time of the up-stroke of piston 77 will be forced through passage 82 past ball check valve 83 and into annular space 10. During the up-stroke of piston 77, check valves 80 and 83 will be seated by the pressure of fluid thereagainst, and at such time the fluid previously moved into cylinder 81 during the down stroke of piston 77 will be forced through passage 84 past ball check valve 85 and into annular space 10 and simultaneously additional fluid will be drawn through passage 86 past check valve 87 and into cylinder 81.

The longitudinal bore 88 through piston rod 68, middle rod 78, and lower rod 89, and communicating bores 90 and 91 in pistons 61 and 77, respectively, together with the annular cut outs 92 and 93 in pistons 61 and 77, respectively, provide continuous lubrication of the entire assembly and thus a minimum of wear. It also will be noted that lower rod 89 is encased in closed balance tube 94, which, upon becoming filled with fluid, will serve to cushion movement of pistons 61 and 77.

The operation of lower pump 13 is identical with that of upper pump 12 and differs therefrom in the drawing only in that the pumping mecha-

nism of pump 13 is shown in Figure 13 at the end of its up-stroke, whereas pump 12 is shown in Figure 12 at the end of its down stroke. Upon repetition of the cycle of operation of hydraulic lift pump 12, the spent power fluid and also the fluid from the associated reservoir will be exhausted into annular space 10, and by virtue of continued operation of pump 12 it will be forced to the well surface and withdrawn therefrom through valve controlled pipe 95.

The fluid from upper reservoir 3 will flow into the interior of casing 2 through perforations 5, and obviously will be prevented from entering openings 30 of screen 24 by reason of production packer 26. Such being the case, it will flow upwardly in casing 2, whence it will pass through openings 96 in skirt 23 into annular space 97 between skirt 23 and sleeve 17. The fluid then will be directed through passage 98 provided in nipple 14 and into first tubing string 7. However, by reason of lower shoe 99 threaded, as at 100 and as at 101, to successive sections 102 and 103 of first tubing string 7 and also sealed, as at 104, against the end of second tubing string 9, it will be noted that continued passage of the fluid upwardly into first tubing string 7 will be blocked and that instead such fluid will be directed through check valve 11 and into the intake end 105 of lower hydraulic pump 13 through the medium of landing nipple 106 in which hydraulic pump 13 is seated within second tubing string 9.

The operation of hydraulic pump 13 is identical with hydraulic pump 12, and is adapted to lift to the well surface fluid from upper reservoir 3. By reference to Figures 1 to 3, inclusive, and in particular to Figures 5 to 11, inclusive, of the drawings, it will be seen that the power fluid to pump 13 is admitted from a source, not shown, through valve controlled pipe 107 which is run initially into first annular space 8 and thence through annular space 33, and terminates as by threading, as at 108, in upper shoe 109 in communication with interconnecting passages 110 and 111. From passage 111 the fluid will pass into second annular space 10, and due to O-ring 41 and O-ring 112 will be caused to enter through a series of ports 113 provided in header 43 into interconnecting longitudinal bore 114 and sleeve 115 and thence into the power side 116 of hydraulic pump 13.

Also by reference to Figures 1 to 3, inclusive, and in particular to Figures 5 to 11, inclusive, of the drawings, it will be seen that the fluid from reservoir 3 exhausted from hydraulic pump 13 will empty into that portion of second annular space 10 between O-ring 112 and landing nipple 106, whence it will be directed through interconnecting passages 117 and 118 provided in lower shoe 99 and through pipe 119 threaded as at 120 in shoe 99. Pipe 119 continues upwardly in annular space 33 to a point above manifold nipple 37 whence it is terminated in a free end 121 in first annular space 8, as shown in Figure 6. The fluid delivered from pipe 119 will continue to be forced upwardly in annular space 8 through the action of hydraulic pump 12, and upon reaching the well surface will be drawn off through valve controlled pipe 122.

Although any suitable, available liquid may be employed as the power liquid, it is preferable to employ clean crude oil which previously has been produced from the reservoirs. This not only provides a readily available source of power liquid but also obviates the problem of separating the

commingled power liquid and reservoir fluid produced from the well.

Each of the hydraulic pumps are disposed at a suitable position along the length of the second tubing string such that fluid from its associated reservoir can enter the pump chamber during operation of the pump piston. It is understood that the power liquid is under sufficient pressure to actuate each of the pumps against the back pressure exerted thereupon by the column of liquid exhausted therefrom.

It is also understood that the invention is not to be limited to the particular hydraulic pump illustrated, but that any suitable conventional hydraulic pumping means may be employed.

We claim:

1. In a system for producing from a plurality of subterranean reservoirs through a single bore hole traversing the reservoirs and including a well casing disposed in the bore hole and provided with perforations adjacent an upper and a lower reservoir, and a first tubing string disposed in the well casing in a manner to provide a first annular space therebetween, the combination of a second tubing string disposed in the first tubing string in a manner to provide a second annular space therebetween and having connected intermediate its length and at the lower end thereof respectively an upper hydraulic pumping means having exhaust ports in the walls thereof, and a header from which is suspended a lower hydraulic pumping means having exhaust ports in the walls thereof, each of said hydraulic pumping means being operable upon the application thereto of power liquid to lift to the surface of the earth reservoir fluid entering thereinto, means for directing the flow of fluid from the upper reservoir into one of the pumping means, means for directing the flow of fluid from the lower reservoir into the other pumping means, means for applying power liquid to the upper and lower pumping means under sufficient pressure to operate the pumps, packing means for isolating the exhaust ports of the upper and lower pumping means, means for directing flow of fluid exhausted from the upper pumping means upwardly through the second annular space, and means for directing the flow of fluid exhausted from the lower pumping means upwardly through the first annular space whereby reservoir fluids from the upper and lower reservoirs will be lifted to the surface of the earth, without the commingling thereof.

2. In a system for producing from a plurality of subterranean reservoirs through a single bore hole traversing the reservoirs and including a well casing disposed in the bore hole and provided with perforations adjacent an upper and a lower reservoir, and a first tubing string disposed in the well casing in a manner to provide a first annular space therebetween, the combination of a second tubing string disposed in the first tubing string in a manner to provide a second annular space therebetween and having connected intermediate its length and at the lower end thereof respectively an upper hydraulic pumping means having exhaust ports in the walls thereof, and a header from which is suspended a lower hydraulic pumping means having exhaust ports in the walls thereof, each of said hydraulic pumping means being operable upon the application thereto of power liquid to lift to the surface of the earth reservoir fluid entering thereinto, means for directing the flow of fluid from the upper reservoir into one of the pumping means,

means for directing the flow of fluid from the lower reservoir into the other pumping means, means for applying power liquid to the upper pumping means through the second tubing string, a third tubing string disposed in the first annular space and adaptable for applying power liquid to the lower pumping means, packing means for isolating the exhaust ports of the upper and lower pumping means, means associated with the exhaust ports of the upper pumping means for directing the flow of fluid exhausted therefrom upwardly through the second annular space, and means associated with the exhaust ports of the lower pumping means for directing the flow of fluid exhausted therefrom upwardly through the first annular space whereby reservoir fluids from the upper and lower reservoirs will be lifted to the surface of the earth, without the commingling thereof.

3. In a system for producing from a plurality of subterranean reservoirs through a single bore hole traversing the reservoirs and including a well casing disposed in the bore hole and provided with perforations adjacent an upper and a lower reservoir, and a first tubing string disposed in the well casing in a manner to provide a first annular space therebetween, the combination of a second tubing string disposed in the first tubing string in a manner to provide a second annular space therebetween and having connected intermediate its length and at the lower end thereof respectively an upper hydraulic pumping means having exhaust ports in the walls thereof, and a header from which is suspended a lower hydraulic pumping means having exhaust ports in the walls thereof, each of said hydraulic pumping means being operable upon the application thereto of power liquid to lift to the surface of the earth reservoir fluid entering thereinto, means for directing the flow of fluid from the upper reservoir into the lower pumping means, means for directing the flow of fluid from the lower reservoir into the upper pumping means, means for applying power liquid to the upper pumping means through the second tubing string, a third tubing string disposed in the first annular space and adaptable for applying power liquid to the lower pumping means, packing means for isolating the exhaust ports of the upper and lower pumping means, means associated with the exhaust ports of the upper pumping means for directing the flow of fluid exhausted therefrom upwardly through the second annular space, and means associated with the exhaust ports of the lower pumping means for directing the flow of fluid exhausted therefrom upwardly through the first annular space whereby reservoir fluids from the upper and lower reservoirs will be lifted to the surface of the earth, without the commingling thereof.

4. In a system for producing from a plurality of subterranean reservoirs through a single bore hole traversing the reservoirs and including a well casing disposed in the bore hole and provided with perforations adjacent an upper and a lower reservoir, and a first tubing string disposed in the well casing in a manner to provide a first annular space therebetween, the combination of a second tubing string disposed in the first tubing string in a manner to provide a second annular space therebetween and having connected intermediate its length and at the lower end thereof respectively an upper hydraulic pumping means having exhaust ports in the walls thereof, and a header from which is suspended

a lower hydraulic pumping means having exhaust ports in the walls thereof, each of said hydraulic pumping means being operable upon the application thereto of power liquid to lift to the surface of the earth reservoir fluid entering thereinto, means for directing the flow of fluid from the upper reservoir into the upper pumping means, means for directing the flow of fluid from the lower reservoir into the lower pumping means, means for applying power liquid to the upper pumping means through the second tubing string, a third tubing string disposed in the first annular space and adaptable for applying power liquid to the lower pumping means, packing means for isolating the exhaust ports of the upper and lower pumping means, means associated with the exhaust ports of the upper pumping means for directing the flow of fluid exhausted therefrom upwardly through the second annular space, and means associated with the exhaust ports of the lower pumping means for directing the flow of fluid exhausted therefrom upwardly through the first annular space whereby reservoir fluids from the upper and lower reservoirs will be lifted to the surface of the earth, without the commingling thereof.

5. In a system for producing independently from two subterranean reservoirs through a single well including a well head, a casing traversing the reservoirs and communicating therewith, a first tubing string disposed in the casing in a manner to provide a first annular space therebetween, and a second tubing string disposed in the first tubing string in a manner to provide a second annular space therebetween, in combination therewith a first and a second hydraulic lift means, each having a power liquid and a reservoir fluid inlet and exhaust ports, the power fluid inlet of the first lift means being connected to the second tubing string whereby power fluid may be delivered through the second tubing string to the first lift means and the exhaust ports of the first lift means communicating with the first tubing string through which exhausted fluid is conducted to the well head, means associated with the reservoir fluid inlet of the first lift means for directing fluid from one of the reservoirs into the first lift means, a third tubing string disposed in the first annular space and communicating with the power liquid inlet of the second lift means for conducting power liquid to the second lift means, means for directing fluid from the other reservoir into the reservoir fluid inlet of the second lift means, and means communicating with the exhaust ports of the second lift means for conducting fluid into the first annular space through which such fluid flows to the well head.

6. In a system for producing independently from two subterranean reservoirs through a single well including a well head, a casing traversing the reservoirs and communicating therewith, a first tubing string disposed in the casing in a manner to provide a first annular space therebetween, and a second tubing string disposed in the first tubing string in a manner to provide a second annular space therebetween, in combination therewith a first and a second hydraulic lift means, each having a power liquid and a reservoir fluid inlet and exhaust ports, the power fluid inlet of the first lift means being connected to the second tubing string whereby power fluid may be delivered through the second tubing string to the first lift means and the exhaust ports of the first lift means communicat-

ing with the first tubing string through which exhausted fluid is conducted to the well head, a fluid chamber communicating with the reservoir fluid inlet of the first lift means, means for directing fluid from one of the reservoirs into the fluid chamber, a third tubing string disposed in the first annular space and communicating with the power liquid inlet of the second lift means for conducting power liquid to the second lift means, means for directing fluid from the other reservoir into the reservoir fluid inlet of the second lift means, and means communicating with the exhaust ports of the second lift means for conducting fluid into the first annular space through which such fluid flows to the well head.

7. In a system for producing from a plurality of subterranean reservoirs through a single well including a casing secured within the well and traversing the reservoirs, a first tubing string disposed within the casing in a manner providing a first annular space between it and the casing, a second tubing string disposed within the first tubing string in a manner providing a second annular space between it and the first tubing string, a first hydraulic lift means interposed in said second string intermediate its ends, a second hydraulic lift means suspended from the lower end of said second string, each of said hydraulic lift means having power liquid inlet and outlet ports and well fluid inlet and outlet ports, means providing communication between one of said reservoirs and the well fluid inlet port of one of said lift means, means providing communication between another of said reservoirs and the well
